RAILWAY SWITCH OPERATING APPARATUS

William E. Smith, Pittsburgh, Pa., assignor to The Union Switch & Signal Company, Swissvale, Pa., a corporation of Pennsylvania

Application July 12, 1939, Serial No. 224,033

3 Claims. (Cl. 74—491)

My invention relates to railway switch operating apparatus, and particularly to apparatus of the type which includes a hand lever for throwing a spring switch.

- 5 In switch operating apparatus of the type described it sometimes becomes necessary or desirable to reverse the position of the switch throwing device while the switch points are held in their trailed positions by the wheels of a vehicle which is stopped on the switch. When this happens, the releasing of the force stored in the spring biasing means tends to jerk the hand-throw lever out of the operator's hands, and one object of my invention is to provide means for 10 preventing this from happening to guard against possible injury to the operator.

Other objects and characteristic features of my invention will become apparent as the description proceeds.

- 20 I shall describe one form of apparatus embodying my invention, and shall then point out the novel features thereof in claims.

In the accompanying drawings, Fig. 1 is a diagrammatic view showing a spring switch A operated by a switch operating mechanism B to which my invention is applicable. Fig. 2 is a top plan view showing mechanism embodying my invention for connecting the lever 30 with the shaft 31 of the mechanism shown in Fig. 1. Fig. 3 is a 25 front elevational view partly in section of the mechanism shown in Fig. 2. Fig. 4 is a side view partly in elevation and partly in section of the mechanism shown in Figs. 2 and 3. Fig. 5 is a fragmentary view showing a portion of the mechanism illustrated in the preceding views in the 30 positions which they occupy during one part of the stroke of the lever 30 from its normal position to its reverse position. Fig. 6 is a view similar to Fig. 3 but showing the parts in the opposite 35 extreme positions from that in which they are shown in Fig. 3.

Similar reference characters refer to similar parts in each of the several views.

Referring first to Fig. 1, the reference character 40 A designates a railway switch comprising, as usual, two fixed rails 1 and 1a and two movable rails 2 and 2a. The movable rails are fastened together by a front rod 5, a head rod 6 and a tie rod 8, and may be moved into a normal or a reverse position by means of a switch operating mechanism B which is connected with the head rod 6 through the medium of an operating rod 9 and a spring connecting rod C. When the switch occupies its normal position in which it is shown 45 in Fig. 1, the movable rail 2 engages the fixed rail

1 and the movable rail 2a is spaced a slight distance from the fixed rail 1a. When the switch is reversed, however, the movable rail 2a then engages the fixed rail 1a, and the movable rail 2 is spaced from the fixed rail 1.

The spring connecting rod C may have any desired construction which will cause the switch points to be held in whichever extreme position they are moved to by the mechanism B with sufficient force to permit facing point moves over 10 the switch without danger of displacement of the points, but which will yield when a train trails the switch, and thereby allow the train to force the switch points to positions opposite to their initially set positions. One form of spring connecting rod which will accomplish the necessary results is shown and described in Letters Patent of the United States No. 1,976,827, granted to Herbert L. Bone, on October 16, 1934, for Railway switch operating apparatus.

The switch operating mechanism B may, for example, be similar to that shown and described in the said Bone Patent No. 1,976,827 just referred to, and the various parts are designated in the drawings by the same reference characters as 20 they are designated by in the patent. It is believed, therefore, that for purposes of my present invention the following brief description of this mechanism will suffice.

The mechanism B includes a motion plate 26 30 which is arranged to be reciprocated between two extreme positions by means of a hand lever 30 through the medium of a shaft 31 and a gear wheel 33. Formed in the motion plate is a cam slot 28 provided with offset end portions which extend parallel to the direction of motion of the motion plate, and with an intermediate connecting portion which extends at an angle to the direction of motion of the motion plate, and this slot cooperates with a roller 34 operatively connected with the operating rod 9 in such manner that the switch will be moved to its normal or to its reverse position according as the motion plate occupies the extreme position shown, or its opposite extreme position. The mechanism also includes 35 a locking plunger 39e which cooperates with a pair of aligned notches 48 in a lock rod L secured to the front rod 5 of the switch A. The locking plunger is biased by means of a spring 39n to a locking position in which, when the switch occupies its normal position, it will enter the notches 48 in the lock rod L and thus lock the switch in its normal position, but the locking plunger is arranged to be moved to an unlocking position, prior to any movement of the switch points away 40 45 50 55 60 65 70 75 80 85 90 95 100 105 110 from their normal positions by the mechanism B, by suitable means indicated diagrammatically in the drawings by a lug 42 provided on the motion plate and cooperating with a lug 39d provided on the locking plunger. The locking plunger is also arranged to be moved to its unlocking position, prior to any movement of the switch points away from their normal positions by a trailing train, through the medium of suitable lock releasing linkage including a bell crank lever 57, substantially as described in the said Bone Patent No. 1,976,827 referred to above.

With the switch A arranged to be operated in the manner described it sometimes happens that a train which has started to trail the switch stops for one reason or another in a position in which the switch points are held in their trailed positions by the wheels of one of the vehicles of the train, and that, while the points are thus held in their trailed positions, an operator attempts to move the switch to its reverse position by means of the switch operating mechanism B. When this happens, the operation of the mechanism releases the energy stored in the compressed spring of the spring connecting rod C, and causes this energy to be transmitted back through the operating rod 9, roller 34, and inclined portion of the cam slot 28 to the motion plate 26, and from thence through the gear wheel 33 to the shaft 31, with the result that the shaft 31 is rotated very suddenly in a counterclockwise direction, as viewed in Fig. 1. Heretofore, it has been customary to secure the hand lever 30 directly to the shaft 31, and when the hand lever is secured directly to the shaft, this sudden rotation of the shaft tends to jerk the hand lever out of the operator's hand, thereby creating a dangerous condition, and in some instances causing damage to the apparatus. In accordance with my present invention, I provide means which I shall now describe for connecting the hand lever 30 with the shaft 31 in such manner that the lever will become automatically disconnected from the shaft in the event of rotation of the shaft in response to energy stored in the spring, under the conditions above described.

Referring now also to Figs. 2 to 5, inclusive, as here shown, the lever 30 is formed with a hub 30a having an integral flange 30b provided with a lug 30c, and with a stud 30d carrying a pawl 30e. The hub 30a of the lever is journaled on the outer end of the shaft 31 adjacent to a driving collar 60 which is fixed to the shaft, and formed on the driving collar is a radially extending lug 61 which cooperates with the lug 30c on the hand lever. The lug 61 also cooperates with the pawl 30e, and is provided in one side with a notch 61a, which, when the parts are in their normal positions in which they are shown in Fig. 3, receives the upper end of the pawl. The pawl is constantly biased to the position in which it enters the notch 61a by means of a coil spring 62, one end of which extends into a hole 30f in the flange 30b, and the other end of which engages the side of the pawl. The pawl is arranged to be automatically disengaged from the notch in response to rotation of the lever in the direction to move the switch to its reverse position, by means of a trip arm 63, and in order to enable the pawl to be readily disengaged from the notch, the upper end of the pawl and the adjacent side of the notch are rounded in the manner shown. The trip arm 63 is pivoted on a pin 64 mounted in a pair of spaced lugs 65 formed on a frame 66 bolted to the side of the mechanism

casing 11, and is biased to a position in which a finger 67 formed on the end of the trip arm projects into the path of movement of the pawl by means of a compressed coil spring 68. One end of the spring 68 extends into a cup 69 formed on the trip arm, and the other end extends into a recess formed in the mechanism case. The right-hand side of the finger 67, as viewed in Figs. 2 and 3, is beveled at 67a for a purpose which will be made clear presently.

With the lever constructed and arranged in this manner, when the lever is rotated in a counterclockwise direction from the position in which it is shown in Fig. 3 to its opposite extreme position to reverse the switch, the lug 30c will engage the lug 61 on the collar 60, and will thus cause the collar 60 and hence the shaft 31 to rotate in response to the rotation of the lever. During this rotation the pawl 30e will, of course, be rotated with the lever, and as soon as the lever has been rotated a relatively short distance, the side of the pawl will move into engagement with the side of the trip finger 67, with the result that during the continued rotation of the lever the pawl will be rotated by the trip finger to the position in which it is shown in Fig. 5, in which position it is completely out of the path of movement of the lug 61. When this happens, if the spring of the connecting rod C is compressed beyond its normal compression, as will be the case if the switch points are then held in their trailed positions by the wheels of a vehicle, the resultant torque which is then exerted on the shaft 31 will cause the shaft and driving collar to rotate rapidly toward their reverse positions, but since the pawl is now out of the path of the lever, the rotation of the shaft will not be transmitted to the lever, and it will be seen, therefore, that the lever will be released of any violent movement. When the lever 30 has been rotated far enough, the pawl will swing clear of the trip finger, whereupon the spring 62 will restore the pawl to its normal position; and, when the lever 30 reaches the position corresponding to the position of the collar, the lug 30c will move back into engagement with the lug 61, and the pawl will swing back into the notch 61a. If the collar has not reached its full reverse position when this happens, the lug 30c will cooperate with the lug 61 on the collar to complete the movement of the shaft 31, and thus complete the movement of the switch points. When the lever occupies its full reverse position, the parts will occupy the positions in which they are shown in Fig. 6.

If the switch points are in their normal positions when the lever 30 is operated to reverse the switch points, there will be insufficient force exerted on the shaft 31 and collar 61 by the springs of the spring connecting rod to cause the shaft 31 to rotate in advance of the rotation of the lever, and while the pawl 30e will be moved out of the recess 61a in the manner above described, the lug 30c will remain in engagement with the lug 61. As soon as the pawl has cleared the trip finger, it will snap back into place in the notch 61a.

When the lever has been rotated to its reverse position and it is subsequently operated to restore the switch points to their normal positions, the torque exerted on the lever will be transmitted to the sleeve through the stud 30d and pawl 30e in a manner which will readily be apparent from an inspection of Fig. 6. During this movement, the pawl will engage the beveled face 67a of the trip finger in the manner shown in dotted lines in Fig. 75.

- 5, and will thus cause the trip finger to move inwardly in opposition to the bias of the spring 68 to a position in which it is out of the path of the pawl without causing any displacement of the pawl, such displacement being prevented under these conditions due to the shape of the notch 61a. As soon as the pawl has passed the trip finger, the trip arm will return to its normal position due to the bias of the spring 68.
- 10 Although I have herein shown and described only one form of railway switch operating apparatus embodying my invention, it is understood that various changes and modifications may be made therein within the scope of the appended claims without departing from the spirit and scope of my invention.
- 15 Having thus described my invention, what I claim is:

1. In combination, a shaft rotatable between two extreme positions and connected with means which at times tends to rotate said shaft quickly toward one extreme position, a driving collar secured to said shaft and provided with a lug, a manually operable lever journaled on said shaft 25 and provided with a lug which cooperates with the lug on said collar during rotation of said lever in one direction to cause said shaft to rotate in response to rotation of said lever, a pawl pivotally attached to said lever and biased into engagement 30 with the lug on said collar and cooperating with the lug on said collar during rotation of the lever in the other direction to cause said shaft to rotate with said lever, and a trip arm effective to move said pawl out of operative engagement with the lug on said collar during rotation of the lever in one direction to permit said shaft to rotate independently of the lever to prevent the lever from being jerked out of an operator's hands.
2. In combination, a shaft rotatable between two extreme positions and connected with means which when the shaft is rotated to either extreme position exerts a yieldable force on it tending to rotate it away from such extreme position, a driving collar fixed to the shaft and provided with a

lug, a lever journaled on the shaft and provided with a lug which when the lever is rotated in one direction cooperates with the lug on said collar to rotate said shaft to its one extreme position, a pawl secured to said lever and biased to a position in which it enters a notch in the lug on said collar and effective during rotation of said shaft in the other direction to rotate said shaft to its other extreme position through the medium of said collar, and a pivoted trip arm biased to a position in which it cooperates with said pawl during rotation of said lever in said one direction to rotate said pawl out of said notch to a position in which said shaft is free to rotate independently of said lever to prevent rotation of the lever by 15 said yieldable force.

3. In combination, a first member rotatable between two extreme positions, a second member rotatable between two extreme positions, a lug on said first member cooperating with a lug on said second member for causing said second member to rotate from one extreme position to another extreme position in response to rotation of said first member from its one extreme position to its other extreme position, a pivoted pawl mounted 20 on said first member, means for holding said pawl in driving engagement with the lug on said second member during rotation of said first member from its other extreme position to its one extreme position, and other means for moving said pawl 25 out of the path of movement of the lug on said second member during at least a part of the movement of said second member in response to movement of said first member toward its other position, whereby said second member is constrained to rotate to either extreme position in response to rotation of said first member to the corresponding extreme position but is free to rotate toward its other extreme position independently of said first member in response to a force 30 applied thereto by means other than said first member.

WILLIAM E. SMITH.
